US0D1033158S

(12) **United States Design Patent** (10) **Patent No.:** **US D1,033,158 S**
(45) **Date of Patent:** **** Jul. 2, 2024**

(54) **CONTAINER ACCESSORIES**

(71) Applicant: **YETI Coolers, LLC**, Austin, TX (US)

(72) Inventors: **Steve Charles Nichols**, Austin, TX (US); **Andy Bondhus**, Austin, TX (US); **Tobias Hotchkiss**, Austin, TX (US); **Mark Carlson Rane**, Austin, TX (US); **John Loudenslager**, Austin, TX (US); **Derek G. Sullivan**, Austin, TX (US)

(73) Assignee: **YETI Coolers, LLC**, Austin, TX (US)

(**) Term: **15 Years**

(21) Appl. No.: **29/844,893**

(22) Filed: **Jul. 1, 2022**

Related U.S. Application Data

(63) Continuation of application No. 29/795,314, filed on Jun. 17, 2021, now Pat. No. Des. 959,208, which is a (Continued)

(57) **CLAIM**

The ornamental design for container accessories, as shown and described.

DESCRIPTION

FIG. 1 is a top, front, right perspective view of container accessories showing our new design;

FIG. 2 is a front view thereof;

FIG. 3 is a top view thereof;

FIG. 4 is a left side view thereof;

FIG. 5 is a right side view thereof; and,

FIG. 6 is a top, front, right perspective exploded view of a container accessories showing our new design.

The broken lines immediately adjacent to the shaded area define the bounds of the claimed design and form no part thereof. The broken lines depicting the remainder of the container accessories form no part of the claimed design.

1 Claim, 6 Drawing Sheets

Related U.S. Application Data

continuation of application No. 29/757,384, filed on Nov. 5, 2020, now Pat. No. Des. 929,814, which is a continuation of application No. 29/673,074, filed on Dec. 11, 2018, now Pat. No. Des. 907,445.
